UNITED STATES PATENT OFFICE.

FRANZ CARL NICOLAUS PARIZOT, OF BREMEN, GERMANY.

SELF-IGNITER FOR GAS-BURNERS.

SPECIFICATION forming part of Letters Patent No. 737,462, dated August 25, 1903.

Application filed May 27, 1902. Serial No. 109,143. (No model.)

To all whom it may concern:

Be it known that I, FRANZ CARL NICOLAUS PARIZOT, a subject of the Emperor of Germany, residing at Bremen, German Empire, 5 have invented certain new and useful Improvements in Self-Igniters for Gas-Burners, of which the following is a specification.

My invention relates to self-igniting attachments for gas-burners, and more particularly to that class of self-igniters in which the igniting mass is brought and held out of the flow of the hot gases after having ignited the gas.

The essential feature of my invention consists of a small ventilator-wheel which is to be mounted above the glass cylinder of a gas-burner and when rotating thus carries the igniters hanging down therefrom out of the flow of the hot gases for preventing injury to 20 the said igniters.

In the accompanying drawings, Figure 1 shows in vertical section a self-igniting attachment with my improvements; Fig. 2, the plan view thereof. Fig. 3 illustrates in front 25 elevation the construction of the ventilator-wheel shown on a larger scale. Fig. 4 is a vertical section thereof.

In the construction of my invention I use a cylindrical cap *b*, which is adapted to be 30 placed over the upper end of the glass cylinder *a* of a gas-burner, so as to cover same partially with its upper conical-shaped end. A needle *c*, made of steel or other suitable material, is secured to the said cap and centrally 35 bent up vertically, as shown in Fig. 1, for receiving the ventilator-wheel above referred to. This latter consists of a plurality of wings *d*—four as shown—made of mica and supported by the arms of an aluminium ring *e*, 40 which latter is carried by a small hood *g*, as shown in Figs. 3 and 4. A glass dab or socket

h is concentrically cemented into said hood *g* or tightened therein by means of asbestos or the like, and a small asbestos ring *i*, inserted in the lower end of said hood, provides 45 means for preventing noise from friction when the ventilator is rotating. Ears *n*, extending from the said arm of the ring *e*, serve for receiving the loop-formed upper ends of two thin wires *k*, of a refractory material, which 50 carry the conical aluminium casings *l l'*, suspended thereon. Within each of these casings a self-igniting mass *o* is suspended, but having its platinum threads *p* not extending below the lower end of said casing. Openings *m* in the sides of said casing *l l'* allow a 55 free passage of the gas, thus insuring ignition. The conical upper end of the cap *b* forms a guide for the flow of the gas, which thus is directed against the igniters. 60

The action of the attachment is obvious. The heat radiating from the flame causes rotation of the ventilator-wheel, and thereby the igniters are brought and held out of the flow of the heat by centrifugal force, and thus 65 protected from being worn by the heat.

I claim—

In a self-igniter for gas-burners, the combination of a cap adapted to be placed on the upper end of a gas-burner cylinder, a needle 70 vertically and centrally secured thereto, a ventilator-wheel mounted on said needle so as to rotate freely thereon, a plurality of wires linked thereto and hanging down therefrom, casings secured to the lower ends of said wires 75 and a self-igniting mass within each of said casings, substantially as and for the purpose described.

FRANZ CARL NICOLAUS PARIZOT.
